UNITED STATES PATENT OFFICE.

OSBORNE I. PRICE, OF FREDERICK, MARYLAND.

WATER-CIRCULATION PUMP FOR AUTOMOBILE ENGINES.

Application filed July 27, 1923. Serial No. 654,194.

To all whom it may concern:

Be it known that I, OSBORNE I. PRICE, a citizen of the United States, residing at Frederick, in the county of Frederick and 5 State of Maryland, have invented a certain new and useful Improvement in a Water-Circulation Pump for Automobile Engines, of which the following is a specification.

My invention relates broadly to automobile engines and more particularly to a construction of water circulating pump arranged to be conveniently installed in a thermo-siphon water cooling system for automobile engines.

One of the objects of my invention is to provide a construction of water circulating pump for automobile engine cooling systems having its elements each individually removable to facilitate the replacement of elements for repair and adjustment.

Another object of the invention is to provide a construction of water circulating pump arranged to be quickly installed in a thermo-siphon water cooling system for automobile engines having its parts arranged so that the lubricating system in the pump is prevented being flooded or reached by the cooling system by slight adjustment which may be made from time to time throughout 30 the life of the pump.

Another object of the invention is to provide a pump construction in which the driving shaft is substantially packed and water sealed and provided with a circuitous path 35 formed by the pump shaft bearing immediately adjacent the impeller end of the pump shaft whereby water from the water cooling system is positively prevented from entering the pump shaft bearing and flooding the lubricating system of the pump.

A still further object of the invention is to provide a water circulating pump for thermo-siphon water cooling systems for automobile engines in which the pump is 45 provided with an adjustable and removable sleeve bearing capable of longitudinal adjustment against the packing adjacent the impeller end of the pump to insure a water tight bearing regardless of natural wear of the packing under conditions of long use throughout the life of the pump.

My invention will be more clearly understood from the following specification and by reference to the accompanying drawings in which:

Figure 1 is a cross sectional view showing

the construction of my water circulation pump for automobile engines; Fig. 2 is a front view of the water circulation pump shown in Fig. 1 with the driving pulley removable to more clearly show the adjustable packing nut by which the pump shaft is sealed immediately adjacent the impeller end of the pump shaft at the entrance of the shaft into the main body of the pump; Fig. 3 is a view of the pump looking in the direction of the two blade impeller which I have designed to secure efficient water circulation; Fig. 4 is a cross sectional view taken on line 4—4 of Fig. 1 showing the arrangement of the pump shaft and key which I employ for longitudinally adjusting the sleeve bearing in the pump and maintaining the pump shaft in desired position by means of the adjustable packing nut; Fig. 5 is a cross sectional view taken on line 5—5 of Fig. 1 showing the wick oiler which I employ in lubricating the pump shaft and bearing; Fig. 6 is a diagrammatic view illustrating the arrangement of my water circulating pump in a water cooling system for automobile engines; Fig. 7 is a cross sectional view of a modified construction of water circulating pump embodying my invention; Fig. 8 is a cross sectional view on line 8—8 of Fig. 7 illustrating the arrangement of the sleeve bearing employed in my pump construction; and Fig. 9 is a perspective view of the removable sleeve bearing which I employ in the main body of the pump with one end abutting the packing immediately adjacent the entrance of the pump shaft into the water conduit and the other end abutting the adjustable packing nut.

My invention finds particular application in automobile construction normally provided with a thermo-siphon water cooling system. However, my invention is not limited to thermo-siphon systems but may be used as an auxiliary to engine cooling systems having an insufficient form of positively driven water circulating pump where it is found that an insufficient radiating surface has been provided for the particular conditions which the engine may be required to fulfill. In thermo-siphon cooling systems the cooling water often reaches a temperature closely adjacent or equal to the boiling point. Continued operation of the engine with the circulating water at high temperature tends to overheat

and actually burn the lubricating oil, even that of the best quality, and the piston and rings tend to expand to such a degree, especially when deprived of the lubricating oil that they seize in the cylinder. This has the tendency of scoring the walls of the cylinders and the friction produced tends to bind the moving parts so tightly that serious results may ensue such as the sticking of the pistons, the burning out of the bearings, and the warping of the valves, all such contingencies working to the detriment of the engine. With overheated lubricating oil there is a tendency for the explosive gasoline mixture in the cylinders to pass the piston rings into the oil pan resulting in loss of compression and inherent loss of power.

In order to meet and overcome the serious disadvantages in thermo-siphon water cooling systems as above referred to I have developed the present construction of water circulation pump with a view of maintaining the temperature of the cylinders below the danger point but at the same time to have it as high as possible to secure maximum power from the gas burned.

Referring more particularly to the drawings reference character 1 represents the main body of the water circulating pump which may be approximately angular in contour having a flange 2 at one end for convenient connection to the water cooling outlet 3 on the automobile engine 4. The other end of the main body 1 may be provided with a flange coupling 5 for connection with the top hose 6 leading to the upper radiator tank 7 included in the usual thermo-siphon water cooling system on automobiles. The main body of the pump is provided with a substantially tubular cylindrical cast portion 8 extending into the water conduit formed by the main body 1 as represented at 9. The cast portion 8 extends outside of the main body which has been represented by reference character 10. The cast portion 8 forms a substantial extended bearing for the pump shaft 11. The pump shaft 11 is screw threaded at its extremity which projects into the water conduit formed by the main body 1 on which is secured a two blade impeller 14. A shoulder 15 is formed on the shaft 11 against which the impeller 14 abuts when the lock nut 16 is screwed upon the end of the shaft at 12. The other end of the shaft 11 is flattened at 17 to enable a pulley 18 to be secured rigidly thereon by means of set screw 19. The shaft 11 is centrally located and aligned within the cast portion 8 by means of a longitudinal, slidable and removable sleeve bearing 20. The cast portion 10 is provided with a groove indent 21 which cooperates with an extended lug 22 on the removable sleeve bearing 20 to prevent rotative movement thereof. The end 65 of the sleeve bearing 20 adjacent the water

conduit through the main body 1 is provided with an annularly chamfered face 23 which bears against the packing 24 secured against the wall 25 of the cast portion 9 forming a positive seal to prevent the entrance of water into the bearing from the water conduit in the main body 1.

A wick oiler 26 is provided which screws into a bore 27 in the cast portion 10 containing lubricant which is continually supplied to the shaft 11 and the bearing 20 by means of wick 28 which is constantly urged by spring 29 against the shaft 11 as represented at 30. The wick 28 passes through aperture 31 in the sleeve bearing 20.

In Fig. 1 I have illustrated a method of maintaining the impeller shaft 11 in alignment in bearing 20. The shaft 11 is provided with an annular groove 32 in which a U shaped key 33 is inserted. The cast portion 10 is screw threaded at 34 to enable the packing nut 35 to be screwed therein. The inner face of the packing nut 35 bears against the portion of the face of key 33 which extends beyond the groove 32. It will be readily seen that rotation of the packing nut 35 in one direction will advance the bearing sleeve 20 in the direction of the impeller compressing the packing 24 to insure the proper degree of seal against the entrance of water into the bearing. This positive seal eliminates the danger of water entering the bearing and flooding the wick oiler. Without this positive seal immediately adjacent the conduit 1 there would be a tendency for the water to float out or displace the oil from the cup 26 by reason of the oil being lighter than the water thereby endangering the pump by continued operation on a dry bearing.

In Fig. 7 I have shown the shaft 11 provided with a shoulder 36. The cast portion 9 is likewise provided with a cooperating shoulder 37. The spacing sleeve 38 is provided between the rear of the impeller 14 and the end of the cast portion 9 to prevent the shaft from going backward. The cooperating shoulders 36 and 37 prevent the shaft from sliding forward. By this arrangement it is unnecessary to groove the shaft 11 in order to maintain it in alignment. The packing nut 35 bears directly upon the end of the bearing sleeve 20 enabling the sleeve to be longitudinally adjusted against the packing at the point of entrance of the shaft into the water conduit. The construction illustrated in Fig. 7 provides a circuitous path immediately adjacent the shaft at the impeller end of the pump by reason of the shoulders 36 and 37 increasing the seal against the entrance of water into the bearing.

In applying my pump construction to thermo-siphon systems it is only necessary to interpose the pump between the outlet of

the engine cooling system and the top hose as represented in Fig. 6, a belt 40 being looped over pulley 18 and over the fan belt drive pulley 41. My invention permits rapid disassembly and insertion of individual pump parts and elements of the bearing when repairs or replacements are necessary.

While I have described my invention in a certain limited embodiment it is to be understood that modifications may be made and that I intend no limitations upon my invention other than are imposed by the scope of the appended claim.

Having thus described my invention, what I claim and desire to secure by Letters Patent of the United States is as follows:—

A water circulation pump for automobile engines comprising in combination a main body forming a water conduit, a tubular cast portion extending into and out of

said conduit forming an inner and outer bearing support, a sleeve bearing carried within said support substantially shorter than said support, a shaft through said sleeve bearing, an impeller secured to the end of said shaft within said main body, an annular groove in said shaft within said outer bearing support, a U shaped removable key carried in said groove said key having a rim extending beyond the circumference of said shaft, said rim abutting one end of said sleeve, an annular screw threaded member carried by the extremity of said outer bearing support having a face abutting the opposite side of the rim of said U shaped key whereby said shaft and sleeve bearing may be longitudinally moved by rotation of said screw threaded member.

OSBORNE I. PRICE.
